UNITED STATES PATENT OFFICE.

JOHN PLANT, OF DOUGLAS, TERRITORY OF ALASKA.

SHOE-HEEL.

1,233,504.

Specification of Letters Patent. Patented July 17, 1917.

Application filed June 13, 1916. Serial No. 103,440.

To all whom it may concern:

Be it known that I, JOHN PLANT, a citizen of the United States, residing at Douglas, territory of Alaska, have invented certain new and useful Improvements in Shoe-Heels; and I do hereby declare the following to be a full, clear, and exact description of the invention, such as will enable others skilled in the art to which it appertains to make and use the same.

This invention relates to improvements in heels for boots, shoes and other foot coverings.

An object of the present invention resides in the provision of a cushioned heel section so associated with a shoe as to be self-adjusting and thereby evenly distribute the wear throughout its surface.

A further object of the invention is to provide a heel section of the above character, embodying means of novel construction and arrangement for its attachment to a shoe.

With the above and other objects of similar nature in view, the invention consists in the construction, combination and arrangement of parts set forth in and falling within the scope of the appended claim.

In the drawings:

Figure 1 is a bottom plan view of the rear portion of a shoe with the invention associated therewith.

Fig. 2 is a longitudinal section taken on the line 2-2 of Fig. 1.

Fig. 3 is an enlarged fragmentary view of the central portion of the device, and

Fig. 4 is a perspective view of one of the rear plates or washers removed.

Referring now more particularly to the accompanying drawings, there is illustrated the rear portion of a shoe 5 including the heel 6.

The invention is shown generally at 8 and comprises a cushioned disk, constructed preferably of highly resilient material such as rubber or similar substance, molded or otherwise suitably formed to provide in its wearing face a central circular recess or counter-sunk portion 9 having an opening 10 in the base thereof. Seated within the recess 9 is a wear plate or washer 11, flat and of a diameter slightly less than the surrounding wall of the recess so as to fit snugly against the base of the latter. Also seated within the recess 9 is a second wear plate or washer 12 of such construction as to present a mini-

mum of bearing surface 13 upon the adjacent face of the plate 11. This plate 12 is centrally depressed as at 14 away from the plate 11 and is further provided with an aperture 15 the walls of which are tapered toward the plate 11, the latter being likewise apertured as at 16 to aline with the aperture 15 and with the opening 10 in the base of the recess.

In applying the disk, the same is disposed upon the under face of the heel 6 as illustrated in Figs. 1 and 2, the plates or washers 11 and 12 being placed, in the manner shown, within the recess 9 and a screw 17 inserted through the alined openings in said plates and disk and driven into the heel as is apparent. The disk is thus securely positioned on the heel while being free to rotate on the screw 17, and as it is the natural tendency when walking to strike the floor or other surfaces at a point to one side of the longitudinal center of the shoe the disk will be caused to revolve slightly and thus evenly distribute the wear throughout its surface.

It will be observed that the plate 11 is frictionally held stationary with respect to the disk while the plate 12 is similarly held stationary by the tapered head of the screw 17, so that during rotation of the disk the plate 11 will move with respect to the plate 12 and thereby present wear upon the reduced portion of the disk.

It will further be noted that the disk is also provided in its wearing face with a circular series of recesses 18 which recesses serve as suction cups to prevent slipping of the wearer.

It will also be observed that as the disk is compressed the outwardly curved periphery of the plate 12 will serve as a scraping edge to loosen from the wall of the recess any accumulation of foreign matter, while it will also tend to prevent the entry of such matter between the plates 11 and 12 where its presence would materially decrease the efficient operation of the heel.

What is claimed is:

A shoe heel comprising a resilient disk provided with a central recess having an opening through its base, a flat wear plate seated in the recess to frictionally engage the base thereof and rotate with the disk, a second wear plate seated in the recess and rotatably engaged upon the first named plate, said second plate being centrally de-

pressed away from the first named plate and having its periphery bent at an angle therefrom to snugly fit within and engage the wall of the recess whereby to provide a 5 scraping edge for loosening therefrom foreign accumulation and preventing its entry between the plates, said plates being centrally apertured to aline with the opening in the base of the recess, and a screw en-

gaged through said alined apertures and 10 opening and adapted to be driven into a shoe.

In testimony whereof, I affix my signature, in the presence of two witnesses.

JOHN PLANT.
